(57) **CLAIM**

The ornamental design for a hammer tacker grip, as shown and described herein.

DESCRIPTION

FIG. 1 is a top perspective view of the hammer tacker grip of this invention.

FIG. 2 is a right side view of the hammer tacker grip of this invention;

FIG. 3 is a left side view of the hammer tacker grip of this invention;

FIG. 4 is a end view of the hammer tacker grip of this invention;

FIG. 5 is a end view of the hammer tacker grip of this invention;

FIG. 6 is a top view of the hammer tacker grip of this invention;

FIG. 7 is a bottom view of the hammer tacker grip of this invention; and,

FIG. 8 is a bottom perspective view of the hammer tacker grip of this invention.
